UNITED STATES PATENT OFFICE.

J. FORMAN PALMER, OF AUBURN, NEW YORK, ASSIGNOR TO HIMSELF, JOHN SEYMOUR, AND SIDNEY W. PALMER, ALL OF SAME PLACE.

TRACTION-ENGINE.

SPECIFICATION forming part of Letters Patent No. 298,667, dated February 5, 1884.

Application filed November 5, 1883. (No model.)

To all whom it may concern:

Be it known that I, J. FORMAN PALMER, of Auburn, in the county of Cayuga and State of New York, have invented certain new and useful Improvements in Traction-Engines; and I do hereby declare that the following is a full, clear, and exact description thereof, reference being had to the accompanying drawings, in which—

10 Figure 1 shows a view in side elevation of so much of a traction-engine with my steering apparatus applied thereto as is necessary in order to show the arrangement, construction, and manner of supporting the different parts 15 of said apparatus; and Fig. 2, a top plan view of the same with the boiler removed.

The object of my invention is to provide an improvement in the steering apparatus for traction-engines; and to this end it consists in the 20 construction, arrangement, and combination of parts, as hereinafter described, and more specifically pointed out in the claims, whereby the engine can be steered by power from the driving-shaft of the engine in either direction, 25 and the speed of the shifting or cramping of the front axle-tree in such steering can be readily and quickly regulated, and whereby the power steering devices can be thrown out of operation and the steering be done by hand 30 without reference to the movement of the driving-shaft of the engine.

In the drawings, A designates the boiler, and B the fire-box.

35 Journalled upon a suitable stud, C, attached to the side of the fire-box frame, as shown, is a spool-shaped pulley or wheel, D, consisting of two friction-cones, D' D'', beveled inward and toward each other, and rigidly connected together by means of the sleeve portion D''.

40 Upon a hub, d, on the inside end of this double friction-wheel is fixed a sprocket or chain wheel, E. Over this runs the chain F, driven from sprocket-pulley G on the shaft of the main crank-wheel, which shaft is, as usual, journalled above the boiler.

45 Supported and journalled in suitable boxes, H H', on brackets I I', attached to the fire-box end and side, respectively, and in box H'' on bracket I'', attached to one arm of the supporting-standard K, fixed to the bottom of the boiler,

as shown, is the shaft L, at its rear end extending back within reach of the engineer or driver, and inclined downward therefrom until its lower end, where it is journaled, is just a little above the level of the front axle-tree, M, 55 of the engine. The extreme rear end of this shaft is squared, as shown, to receive a crank, N, (represented in dotted lines,) when it is desired to turn the shaft by hand-power. This shaft is provided with fixed collars l and l', to 60 prevent its longitudinal movement in its journal-boxes. The collar l bears against the rear end of the sleeve l'' on the shaft, which sleeve, at its front end, bears against the rear end of bearing-box H. The collar l' abuts against 65 the forward end or face of box H'. Any other of the well-known means in common use for the same purpose on revolving shafts can of course be employed.

Pivoted upon shaft L is the double journal-box M', in which is journalled the short shaft N', parallel with the other shaft. This double box, in plan view, as shown in Fig. 2, consists of the main part m, having at each end a portion, m', extending outward at right angles to 70 the rest. The outer face of each of these raised portions is provided with two half-journal-bearings, one for each shaft. The bearings are made complete by covering-plates provided with corresponding half-bearings, which plates 75 are to be held in place and fastened by suitable screws or bolts.

Upon the long shaft L, and between these journal-bearing portions of box M, is fixed the long-toothed pinion O. The short shaft 85 N' is journalled so as to revolve and be capable of longitudinal movement in its bearings in box M, and upon this shaft and gearing with pinion O is fixed the gear-wheel P. Upon the front end of this shaft is the friction-cone 90 or bevel-wheel Q, which, when the box M is upright, is situated between and just out of contact with the friction-cones or bevel-wheels D' D'', described above. The beveling of the cone Q of course corresponds with that of 95 the latter, so that proper frictional contact shall be made and maintained when the former is brought against either of the latter.

Upon the rear end of shaft N' are fixed two collars, n n, between which is held from 100

gitudinal movement the loose sleeve R. To this sleeve is pivoted the lever S by means of the pin n' on the former and the slot s in the latter. This lever is fulcrumed on a pivot-
5 pin, s' , on sleeve t'' on shaft L. With this arrangement the short shaft can, by means of the lever, be slid back and forth in its bearings in box M, so that the friction wheel or cone on its end will be carried away from or
10 toward the central sleeve connecting the two beveled friction-wheels D' D''. Such movement is caused by a movement of the lever S back and forth upon its fulcrum-pin s' . As this pin is upon the sleeve t'' , which is free to
15 turn on shaft L, the lever can also be turned over from side to side, carrying with it the shaft N' and box M, both lever and box having the shaft L as the pivot upon which they turn or rock. The object of this arrangement
20 and construction will be fully explained hereinafter.

The front and lower end of the shaft L is provided with a bevel-pinion, T, which gears with the bevel-gear wheel U on the end of the
25 screw-shaft V, which is journaled in boxes on the lower ends of the stand or bracket arms K K. This shaft, of course, is to be held from longitudinal movement in the boxes. Upon this screw-shaft is fitted the sleeve X, screw-threaded interiorly to fit the thread on the
30 shaft. Surrounding this sleeve, and pivoted to it above and below, is a ring, Y, which, as shown, is made elliptical, so as to admit of its turning on its vertical pivots to a considerable
35 degree in either direction without striking against the sleeve or shaft. The lower side of this ring is provided with a fixed sleeve, y', adapted to receive the rear reduced end of the forked piece Z, the lugs z z upon the front end
40 of which are suitably pivoted, by the bolt Z', between ears z'' z'', fixed on the rear side of the front axle-tree of the engine. The reduced rear end of the piece Z is, as shown, capable of play back and forth in the sleeve y' as the
45 screw sleeve or nut X is caused to travel back and forth on the screw-shaft by the revolution of the latter, and the distance of the sleeve from the pivotal point of the axle-tree is changed.

50 To the bottom of the boiler, and above the ears z'' z'', are the lugs or ears z''', so situated that if the bolt Z' be drawn out and the fork Z be swung upward the bolt can be passed through lugs z z and ears z''', and the fork be turned up out of the way, so as to allow its front axle to swing freely on its pivot.

The operation of my apparatus is as follows: While the engine is in operation the double cone wheel or spool is caused to revolve by means of its connection with the sprocket-pulley on the revolving crank-shaft. By rocking the lever to one side or the other, the friction-cone on the short shaft N' can be brought into contact with either one of the cones D' D''. Said shaft can then, by this means, be caused to turn in one direction or the other, according to which one of the cones

D' D'' its friction-cone is brought into contact with. As the long pinion on shaft L is always in gear with the toothed wheel on shaft 70 N', said shaft L and the transverse screw-shaft V, by means of the connecting-gearing described, will be caused to turn in one direction or the other, according to the direction of the revolution of the short shaft. A ready 75 means of causing the screw sleeve or nut X to travel in one direction or the other, to swing the front axle-tree to guide the machine, is thus provided. By also throwing the lever forward or back upon its fulcrum 80 on the sleeve on shaft L, the shaft N' can be slid forward or back, and the place of contact between the friction-cone on its end and either one of the cones D' or D'' be carried nearer to or farther from the center of such cone. Upon 85 the distance of the place of contact from the center of the cone, of course, depends the speed at which the cone on shaft N' will be driven. The movement of the lever to one side or the other then determines the direction 90 in which the travel of the engine will be changed, and the movement of the same lever forward or back the speed of such change of direction. When the lever is upright, the friction bevel wheels or cones are out of contact with each other, and, if desired, the shaft 95 L can then be turned by means of the crank, by hand, to turn the front axle in either direction independently of the operation of the engine. 100

With my apparatus, as shown and described, the steering, instead of being done by hand, as heretofore, by slow and laborious means requiring the special and sole attention of one man, can be accomplished by power from the 105 engine itself, governed as to the speed and direction of its action by the movements of a single lever. With it there is also means provided, as described, for cramping the front axle and wheels, as desired, by hand and irrespective of the fact of the engine being in or out of action. 110

I do not intend to claim herein, broadly, means for guiding or steering a traction-engine driven by power from the engine itself, nor, broadly, means for causing the front axle to be swung on its pivot in either direction by such power, as such means are substantially described and claimed in another application filed by me of even date with this; nor do I 120 intend to claim herein the means, as shown and described, adapted to be actuated by power from the engine or by hand, to guide the engine, as such are substantially described and claimed in the application referred to 125 above.

Having thus fully set forth the nature and merits of my invention, what I claim is—

1. In combination with the double-coned pulley driven by power from the engine, gearing for shifting the front axle to guide the machine, and connecting mechanism between the pulley and such gearing, whereby the speed at which and the direction in which the axle- 130

shifting gearing will be driven from the pulley can be changed at will, substantially as shown and described.

2. In combination with the shaft L, journaled in fixed bearings, and adapted through suitable gearing to cause the front axle of the machine to be shifted as the shaft is revolved, the connecting-gearing between such shaft and the main driving-shaft of the engine, whereby 10 the shaft L can be caused to revolve by power from the engine, and means for throwing such connecting-gearing out of action, for reversing its action upon the shaft, and for changing the speed of such action, substantially as 15 shown and described.

3. In combination with the shaft L, adapted through connecting-gearing to cause by its revolution the front axle of the machine to swing on its pivot to guide the machine, the 20 double friction cone or pulley D, driven by power from the engine, the journal-box M, pivoted and rocking on the shaft, the gear-wheel fast on the shaft, the short shaft journaled in the box parallel to shaft L, the pinion 25 on the short shaft gearing with the wheel on the other shaft, the friction-cone on the end of the short shaft and situated between the two cones of the double friction-cone, and means for rocking the double journal-box on 30 the long shaft to carry the cone on the short shaft into contact with the face of one or the other of said cones, substantially as and for the purpose set forth.

4. In combination with the shaft L, for shifting the front axle on its pivot through suitable connecting mechanism, the box M, pivoted and rocking on the shaft, the long-toothed pinion fast on said shaft and gearing with the short-toothed wheel on the shaft N', journaled 40 and capable of sliding motion in the box parallel to shaft L, the friction-cone on the end of shaft N', situated between the friction-cones of the double friction pulley or spool D, driven by power from the driving mechanism of the 45 engine, and means for sliding the shaft N' in the bearings and rocking the journal-box on shaft L, substantially as and for the purpose set forth.

5. In combination with the sprocket-pulley 50 on the end of the crank-shaft of the engine, the sprocket-chain, the sprocket-wheel fixed to the double friction cone or spool, the shaft

for operating the axle-shifting mechanism, the long pinion on such shaft, the journal-box pivoted on the shaft, the short shaft journaled 55 and sliding in the box, the toothed wheel fixed on this shaft and gearing with the long pinion, the friction-cone on the end of the shaft and situated between the faces of the double cone, and a lever adapted to slide the short shaft 60 in its bearings and to rock the journal-box upon the shaft on which it is pivoted, substantially as and for the purpose described.

6. In combination with the shaft L, the box M, pivoted and rocking upon it, the shaft N', 65 journaled and sliding in said box, and provided with a fixed gear-wheel in mesh with a long-toothed pinion on shaft L, and the lever S, fulcrumed on a sleeve on shaft L, and pivotally connected with and embracing a sleeve 70 on shaft N', which is prevented from longitudinal motion on said shaft, all substantially as shown and described, so that by the same lever the box can be rocked on shaft L, and the shaft N' can be reciprocated in its bearings 75 in the box.

7. In combination with the fork Z, hinged to the front axle, the transverse screw-shaft V, journaled in supports from the boiler or engine-frame, and adapted to be revolved in 80 either direction by suitable actuating means, the screw sleeve or nut X, traveling on shaft V, and the ring Y, embracing the sleeve and pivoted thereto above and below, as shown, and provided with a fixed sleeve, y', in which 85 is inserted so as to be capable of longitudinal play therein the reduced end of the axle-shifting fork Z, substantially as and for the purpose set forth.

8. In combination with the axle-shifting 90 fork Z, the perforated lugs attached to the bottom of the boiler, and so situated that when the fork is detached from the front axle and swung upward its front ends will come close beside the lugs, and the pivot-bolt z' can be slid 95 through the latter and the ends of the fork, substantially as and for the purpose set forth.

In testimony that I claim the foregoing I have hereunto set my hand this 3d day of October, A. D. 1883.

J. FORMAN PALMER.
